UNITED STATES PATENT OFFICE.

THOMAS A. WESTON, OF PHILADELPHIA, PENNSYLVANIA, ASSIGNOR TO HIMSELF AND JOHN HEINS, OF SAME PLACE.

IMPROVEMENT IN FRICTION-CLUTCHES.

Specification forming part of Letters Patent No. 157,661, dated December 8, 1871; application filed September 8, 1874.

CASE C.

To all whom it may concern:

Be it known that I, THOMAS A. WESTON, of Philadelphia, Pennsylvania, have invented an Improved Brake-Clutch, of which the following is a specification:

The object of my invention is to clutch a hoisting-barrel or other driver to, and release it from, a shaft with less abruptness than by ordinary friction-clutch devices; and this object I attain by the device illustrated in the side view, Figure 1, vertical section, Fig. 2, and the section, Fig. 3, of the accompanying drawing.

A is the driving-shaft, to which is secured the friction-wheel B, having an outer flange *a*, and inner flange, *b*, to the former of which is adapted a friction-band, D, and to the latter a friction-band, E. G is a hoisting-drum adapted to the shaft A, and loose on the same, excepting when clutched in the manner explained hereafter; and this barrel has an extended flange, *h*, to which, by an annular rib, *e*, is secured an annular plate, H, and between the latter and the said flange *h* is the double-flanged friction-wheel above mentioned. To the conical hub of this friction-wheel is adapted a friction-clutch, K, which can be moved to or fro on the shaft A by a suitable lever; and to this friction-clutch is secured an arm, L, a pin, *m*, on the outer end of which passes through a segmental slot, *f*, in the annular plate H, one end of the inner friction-band E being connected to the said pin *m*, and the other end to a pin, *n*, on a lever, M, which is hung to a pin, *p*, on the annular plate H, and which has a pin, *q*, for receiving one end of the outer friction-band D, the other end being connected to a pin, *t*, on the annular plate H.

The above-mentioned pin *n* on the lever M and the pin *q* on the same lever pass through segmental slots in the annular plate H, as shown in Fig. 1.

Supposing the shaft A to be revolving in the direction of the arrow, Fig. 1, and the clutch K to be moved into frictional contact with the hub of the friction-wheel B, the arm L will be instantly moved in the direction of its arrow, and will tighten the inner friction-

band E to the inner flange *b* of the friction-wheel; but as this band E is connected to the band D through the medium of the lever M, it must operate that lever and tighten the outer friction-band D to the outer flange *a* of the friction-wheel.

In other words, the inner friction-band is the first to embrace its flange of the friction-wheel. Before a tight embrace is accomplished, however, the outer friction-band begins to embrace its flange; hence the clutching of the barrel G to the shaft, although rapidly accomplished, is not so abrupt as when one friction-band only is employed, owing to the fact that the action of one friction-band is slightly in advance of that of the other.

On withdrawing the friction-clutch K from the hub of the friction-wheel, a spring, *w*, acting on the arm L, and a like spring on the lever M, will cause the expansion of both friction-bands, and the hoisting-barrel G will be at liberty.

It will be understood that my invention is quite as applicable to any wheel, or other driver, as to the hoisting-drum, and that other frictional devices may be substituted for the friction-clutch K.

It will also be understood that three, or even more, friction-bands may be used where a still more gradual clutching of the driver to the shaft is required, the contraction of one band depending upon and succeeding that of the other.

I claim as my invention—

The combination, with the barrel G, or other driver, of a friction-wheel, B, to which are adapted two or more friction-bands, connected together through the medium of a lever or levers, M, and operated one in advance of the other, all substantially as set forth.

In testimony whereof I have signed my name to this specification in the presence of two subscribing witnesses.

THOS. A. WESTON.

Witnesses:

E. H. BAILEY,
HARRY SMITH.
